UNITED STATES PATENT OFFICE.

CARL H. STAHLER, OF SONORA, CALIFORNIA.

BRAKE.

Application filed October 8, 1923. Serial No. 667,300.

To all whom it may concern:

Be it known that I, CARL H. STAHLER, a citizen of the United States, and a resident of Sonora, county of Tuolumne, State of California, have invented a new and useful Brake, of which the following is a specification.

This invention relates to brakes as used on vehicles, or revolving machinery generally, but has particular reference to brakes on automobiles as used on the outer surface of brake drums secured to the wheels thereof.

The principal objects of my invention are to produce a contracting band brake adaptable to the use mentioned which will give a more powerful and more uniform grip on the brake drum than the band or external brakes now in use, and this in a structure of great simplicity.

I achieve my objective in the construction shown in the drawings hereto, and in which:

Figure 1 is a side elevation, partly in section, showing my brake in position around the outer surface of a brake drum.

Figure 2 is a cross section of Figure 1 along the line 2—2 showing one of the guiding members for the band;

Figure 3 is a section along the line 3—3 of Figure 1 showing one of the pressure distributing rollers; and

Figure 4 is an enlarged perspective sketch showing the slotted anchorage end of the band with the wrapped portion extending therethrough.

By a glance at Figure 1 it will be seen that my new arrangement consists essentially of a brake band wrapping entirely around the drum, passing the anchorage end and again making a turn around the drum outside of the first wrapping producing a double or superimposed coil effect.

The brake drum is designated (1), the contracting band (2) which is suitably lined with brake lining (3) secured to the band by rivets (4). The anchorage end is designated (5) and is anchored at (6) to the vehicle or machine (not shown).

The anchorage end is apertured at (7), as shown best in Figure 4, and reinforced by the anchorage lug as shown at (16) and the free end is notched or reduced in width as shown at (8) to freely pass the aperture, after which it is wrapped around the first wrapping as shown at (9) spaced therefrom

by a plurality of pressure rollers (10) carried on brackets (11) secured to the secondary wrapping and is guided laterally by brackets (12) secured to the first wrapping. The final or tensioning end of the band is secured at (13) to any suitable tensioning member, here shown as a brake rod (14) having an adjusting turn buckle (15).

Figure 3 shows clearly in cross section the pressure rollers (10) bearing on the first wrapping (2) of the brake band, and Figure 2 shows the outer wrapping (9) guided in the brackets (12). In Figure 1 it will be observed that the rollers (10) and rivets (4) are so spaced relative to each other that the rollers have a smooth unbroken surface of the band to roll on in tightening the brake as the band is pulled by the rod (14) to actuate the brake. In Figures 1 and 2 are shown fingers (17) extending from brackets (12) and overlapping the drum edge to prevent the brake working over bodily into the spokes of the wheel.

The material of which my brake band is made is preferably spring steel, so that it will contract evenly against the drum when the rod is pulled and release evenly when the rod is reversed or released, and also so the outer wrapping will exert sufficient pressure on the rollers without undue flattening between the rollers where it is unsupported thereby. While I show rollers for applying the pressure to the inner from the outer wrapping it is apparent these could be simple blocks, or be dispensed with altogether, but the use of rollers as shown greatly reduces the friction otherwise developed.

In operation, my band when pulled contracts upon the drum in the usual way but by reason of the extra wrapping and rollers it is further forced against the drum evenly all around, thus greatly increasing the effectiveness of the brake by utilizing the entire effective braking surface of the lining instead of wearing it principally at two places only as with the bands in ordinary use.

I claim:

1. In a band brake, a drum, a band wrapped therearound in overlapping layers, rollers between and spacing the layers and brackets extending from one of the layers revolvably supporting the rollers.

2. In a band brake, a drum, a band wrapped therearound in overlapping layers, rollers between and spacing the layers and

brackets extending from one of the layers revolvably supporting the rollers, and means for laterally aligning the layers.

3. In a band brake, a drum, a band wrapped therearound in a double overlapping relation, brackets carried by the outer wrapping, rollers rotatably carried by the brackets and arranged to bear against the inner wrapping upon tightening the band.
- 10 4. In a band brake, a drum, a band wrapped therearound in a double overlapping relation, brackets secured to the inner wrapping for laterally guiding the outer

wrapping, brackets carried by the outer wrapping, rollers rotatably carried by the 15 brackets and arranged to bear against the inner wrapping upon tightening the band.

5. A contracting band for a brake drum, said band being of resilient metal notched for passing itself to form a double concentric loop, brake lining riveted to the inner side of the inner loop and rollers carried by the outer loop spaced to bear on the inner loop between the rivets.

CARL H. STAHLER.
